O. A. TOFFTEEN

FIRE BOX INNER CASING

Filed Nov. 5, 1925

Patented July 26, 1927.

1,636,761

UNITED STATES PATENT OFFICE.

OLOF A. TOFFTEEN, OF CHICAGO, ILLINOIS.

FIRE-BOX INNER CASING.

Application filed November 5, 1925. Serial No. 66,918.

This invention relates more particularly to an inner casing or oven adapted to be positioned within a boiler fire box to surround an oil burner nozzle and afford a combustion chamber positioned to direct flames against an apertured fire arch also positioned within the fire box in a position to coat with said inner casing to afford a circuitous pathway for the flames of combustion through the fire box of the boiler.

It is an object of this invention to provide a partitioned hollow auxiliary housing or casing within a boiler fire box around an oil burner nozzle.

It is also an object of this invention to provide a boiler fire box with a hollow auxiliary oven or housing surrounding a fuel supply nozzle and constructed to supply a plurality of currents of air into said auxiliary housing to be carbureted with the fuel to form flames which are adapted to be guided through the fire box by means of the auxiliary housing and a fire arch associated therewith.

It is an important object of this invention to provide a boiler fire box with a hollow partitioned auxiliary housing or oven constructed of a carborundum product or of fused silicon carbide, said auxiliary housing adapted to surround a burner and furthermore having adjustable means whereby an additional draft of air may be established through an entrance opening in said auxiliary housing.

Other and further important objects of this invention will be apparent from the disclosures in the specification and accompanying drawings.

The invention (in a preferred form) is illustrated in the drawings and hereinafter more fully described.

On the drawings:

Figure 1 is a fragmentary interior view of a boiler fire box illustrating a pair of inner casings or ovens embodying the principles of this invention and showing one of said inner casings in section.

Figure 2 is a vertical central section taken longitudinally through the fire box on line II-II of Figure 1 with parts broken away.

Figure 3 is a fragmentary detail section of the inner casing or oven taken on line III-III of Figure 2.

As shown on the drawings:

The reference numeral 1 indicates a boiler fire box having a front door 2 and a plu-

rality of flues or pipes 3. The fire box 1 is provided with a grate 4 upon which is mounted a fire arch constructed of a carborundum product or fused silicon carbide 60 and consisting of a hollow vertical wall 5 and an upwardly and forwardly inclined hollow top wall 6 having a plurality of air outlet or supply apertures 7 in the bottom wall thereof and a plurality of end apertures 8. The fire arch 5-6 is positioned near the rear end of the fire box and extends transversely thereacross.

Positioned upon the fire grate 4 is an improved inner casing or oven constructed of 70 carborundum or of fused silicon carbide and embracing a hollow front wall 9 provided with an arched opening or doorway 10 through which an oil or fuel supply pipe 11 projects. A fuel distributer or oil nozzle 12 is mounted on the inner end of the fuel supply pipe 11. Mounted on the front face of the front wall 9 are a pair of guides 13 for holding a lower door section 14 and an upper door section 15 in position to normally close the entrance opening 10. The door sections 14 and 15 are notched to fit around the fuel supply pipe 11 when said doors are in their closed positions. Connected with the upper edge of the front wall 9 is a hollow top wall 16 closed at its rear end. The top wall 16 is supported at both sides by a pair of hollow side walls 17 which are closed at their rear ends. Positioned within each of the hollow walls 17 is an 80 upright partition 18 which extends from the fire grate 4 to within a short distance of the top wall 16. The partition 18 divides the interior of each of the side walls into a front chamber 19 and a rear chamber 20. 90 The lower end of each of the front chambers 19 of the side walls is closed by means of a bottom partition or plate 21. Both of the chambers 19 and 20 of each side wall communicate at their upper ends with the chamber 22 in the top wall. The top wall chamber 22 and the front side wall chambers 19 communicate with the chamber 23 of the front wall 9. The casing walls 9, 16 and 17 afford a combustion chamber 24 within the inner casing or oven, said combustion chamber being open at the rear end to permit escape of the flames against the vertical wall 5 of the fire arch. The fire arch acts to direct the flames upwardly in a circuitous path through the boiler fire box.

A liquid fuel is supplied through the fuel

supply pipe 11 which projects through the front opening or entrance 10 of the inner casing or oven. The fuel oil is adapted to be distributed and fed into the combustion chamber 24 by means of the fuel supply nozzle 12. Air is supplied to the combustion chamber 24 through the fire grate 4 and is also supplied through the entrance opening 10 by a current of air which passes upwardly from the fire grate into the rear chambers 20 of the side walls and then passes into the top chamber 22 and over the upper ends of the side wall partitions 18 into the front side wall chambers 19. Air from the top wall chamber 20 and from the front side wall chambers 19 is thus permitted to enter the front wall chamber 23 and pass inwardly through the opening 10 into the combustion chamber 24 around the fuel supply nozzle 12. The different currents of air entering the combustion chamber 24 are thus carbureted with fuel from the fuel burner or nozzle 12 to produce a fuel mixture which is adapted to be readily ignited due to the fact that the auxiliary streams of air entering the front end of the combustion chamber 24 from the hollow chambers 22, 19 and 23 of the inner casing are heated. When an additional quantity of air is desired to pass through the combustion chamber 24 the upper closure plate or door 15 may be adjusted to permit air from below to pass upwardly through the fire grate between the door sections 14 and 15 and through the entrance opening 10 of the front wall of the inner casing. It will thus be seen that the improved hollow inner casing or oven is adapted to provide an arrangement whereby both cold air and superheated air may be admitted into the combustion chamber 24 to be carbureted with fuel from the nozzle 12. The fuel mixture when ignited produces extremely hot flames which are permitted to escape through the open rear end of the combustion chamber 24 and strike against the hollow upright wall 5 of the fire arch. This wall acts to direct the flames upwardly so that they will pass forwardly over the top wall 16 of the inner casing and below the inclined wall 6 of the fire arch. In their upward passage through the fire box the flames are supplied with an additional quantity of superheated air issuing from the lower apertures 7 and the end apertures 8 of the top wall 6 of the fire arch. The flames are adapted to pass forwardly around the apertured front end of the fire arch wall 6 and are then directed rearwardly so that they will pass between the flues or pipes 3 of the boilers.

As illustrated in Figure 1 a plurality of improved inner casings or ovens may be positioned adjacent one another within the fire box upon the boiler grate 4. The inner casings or ovens coacting with the fire arch

5-6 thus afford an improved means whereby flames of intense heat may be circulated through a circuitous path in the boiler fire box to cause heating of the boiler tubes or pipes 3.

I am aware that many changes may be made and numerous details of construction may be varied through a wide range without departing from the principles of this invention, and I therefore do not purpose limiting the patent granted hereon otherwise than necessitated by the prior art.

I claim as my invention:

1. The combination with a boiler fire box, of a hollow apertured fire arch mounted therein, an inner casing mounted within said fire box at a distance from the front wall of the fire box and below the fire arch and open at both ends, said inner casing having hollow walls, means for adjustably closing one end of the casing and a fuel supply device projecting into said fire box and into said inner casing to supply fuel to the interior of said inner casing for carburization with pre-heated air issuing from said hollow casing walls and with the air entering the fire box below said inner casing.

2. The combination with a boiler fire box, of an inner casing spaced from the front wall of the fire box and constructed of fused silicon carbide and comprising hollow side walls closed at the rear ends, a hollow top wall closed at the rear end, and hollow front wall, said hollow front wall having an opening therein, and adjustable means for closing said opening.

3. The combination with a boiler fire box, of an inner casing comprising hollow top, side and front walls, said top and side walls closed at their rear ends, partitions in said hollow side walls to divide the same into a plurality of chambers, said front wall having an opening therein, adjustable means for closing said opening, a fuel supply pipe projecting into the fire box and into said casing through said adjustable means, and a fuel supply nozzle on the inner end of said fuel supply pipe within said inner casing.

4. A fire box inner casing comprising a hollow top wall closed at its rear end, a hollow front wall having an entrance opening therein, hollow side walls connected with said hollow top wall and with said front wall and closed at their rear ends, partitions in said hollow side walls, guides on said hollow front wall, slideable means in said guides controlling the supply of air through said front wall opening, and fuel supply means projecting through said slideable means and front wall opening into the inner casing.

5. The combination with a boiler fire box, of a fuel supply nozzle projecting therein, a chambered casing mounted within said

fire box and spaced from the front wall thereof and enclosing said fuel supply nozzle, said inner casing being open at its rear end and having an opening in the front wall 5 thereof, guides on said front wall, and partitions in said guides for closing said front wall opening, with one of said partitions adjustable with respect to the other.

6. The combination with a fire box and 10 fire grate thereof, of an inner casing mounted on said fire grate and comprising hollow side walls closed at their rear ends, a hollow top wall closed at its rear end, and a hollow front wall, said front wall having 15 an entrance opening therein, adjustable means for closing said entrance opening, fuel supply means projecting through said opening into said casing between said adjustable means, and vertical and horizontal

partitions in said hollow side walls for dividing the same into a plurality of chambers. 20

7. The combination with a fire box and a fire arch therein, of an inner casing mounted in said fire box between the fire arch and the front wall of the fire box and spaced 25 from both the fire arch and said front wall, said inner casing being constructed of a refractory material having hollow walls, angled partitions within certain of said walls, and a fuel supply device projecting into the 30 fire box and into said inner casing, said inner casing being open at both ends and at the bottom, and adjustable means for controlling the opening at one end of said casing. 35

In testimony whereof I have hereunto subscribed my name.

OLOF A. TOFFTEEN.
